WIRE FABRIC

Raymond J. Guba, Philadelphia, Pa., assignor to
 Audubon Wire Cloth Corporation, Philadelphia,
 Pa., a corporation of New Jersey

Application September 17, 1935, Serial No. 40,898

3 Claims. (Cl. 198—201)

My invention relates to woven wire belts and/or fabrics and the method of making the same, and more particularly to belts or fabrics of the type composed of a plurality of interlocking and interlacing, helically twisted wires which are associated and arranged in the formation of such belts or fabrics.

My present improvements are directed to a belt or fabric of the type illustrated and described in my application for patent filed December 18, 1933, Serial No. 702,969, wherein I have disclosed a belt made up of two sets of helically twisted wires in which the alternate wires are twisted in opposite directions on opposite sides of the fabric; said twisted wires being so assembled and fashioned as to render the belt incapable of running off the drive rolls. This condition is effected by alternating the wires of one twist with those of the opposite twist on each face of the belt. Considering each face of the belt as made up of pairs of wires, one wire of each pair will be of dextrorsal twist, while the other wire of each pair is of sinistrorsal twist.

A belt of this type is of double thickness, the dextrorsal wires being interlocked with each other and interlaced with the sinistrorsal wires, and the sinistrorsal wires are interlocked with each other and interlaced with the dextrorsal wires. A sinistrorsal wire underlies each dextrorsal wire, and vice versa, and a dextrorsal wire on one face of the fabric is interlaced with a sinistrorsal wire on the other face of the fabric, and vice versa.

A further object of my invention is to provide a belt or fabric of this type with means that will insure stiffness transversely of the same, such means being preferably in the form of straight wires disposed in interlocking bights of the respective pairs of dextrorsal and sinistrorsal wires, and being connected to at least one marginal edge of the belt. When single connections with the marginal edges of the belt are effected, it is preferable that the end of one wire be connected to one margin and that the opposite ends of adjoining wires be connected to the opposite margin, and so on throughout the full extent of the belt. By preference, these straight, crosswires are associated with each group of bights of the respective interlaced dextrorsal and sinistrorsal wires throughout the full extent of the belt.

A further object of my invention is to provide elevated selvages for the belt in order to provide means that will prevent lateral displacement of objects carried by the belt, and these elevated

selvages are produced by interlocking short wires of right- and left-hand twist with the right- and left-hand twisted wires of a layer of the belt, which may be the upper layer when the belt is in use. In the present instance, one set of the short selvage-forming wires of sinistrorsal or left-hand twist is shown in alignment with and as interlocking with belt wires of sinistrorsal or left-hand twist at one margin or edge of the belt—the right-hand side, for instance—while at the opposite margin or edge of the belt, one set of the short, selvage-forming wires of dextrorsal or right-hand twist interlock with belt wires of dextrorsal or right-hand twist, with which they are in alignment. These selvages are further built up by interlocking with the first set of short, selvage-forming wires additional short, selvage-forming wires of proper twist, which additional wires are in alignment with but do not engage the belt-forming wires. These short, selvage-forming wires may be said to be in pairs; one wire of each pair being interlocked with the helices of a belt wire of the same twist at one margin of the belt and having its ends secured thereto, while the other short wire of each pair is interlocked with the adjacent short wires and overlies a belt wire of opposite twist. The short, selvage-forming wires interlocking with the belt wires have their ends connected thereto, while the intermediate short, selvage-forming wires have their ends connected to the adjacent short wires with which they are interlocked. Any or all of these connections may be made by looping the ends of the wires together, or such ends may be welded, depending upon the circumstances of manufacture or the character of work to be performed by the belt. While I have shown two sets of selvage-forming wires at each edge or margin of the belt, it will be understood that higher selvages may be provided by interlocking as many sets of short wires as may be necessary to give selvages of the desired height, and that it is within the scope of my invention to provide elevated portions made of short, helically twisted wires interlocking with the belt wires intermediate the marginal edges of the belt and extending longitudinally of the same. Additionally, I may provide the belt with transverse ridges forming flights for the lifting of articles conveyed thereby, by extending extra wires the full width of the belt and interlocking the same with belt wires of similar twist; such ridges usually comprising a plurality of wires which may be built up to any

desired height in the same manner in which the selvages are formed.

While, in most instances, the elevated portions—particularly the selvages—will be on one side or surface of the belt or fabric, it is within the scope of my invention to apply elevated selvages to both sides or surfaces of the belt. These elevated portions, whether on one or both surfaces of the belt, do not affect the flexibility of 10 the same.

These and other features of my invention are more fully set forth hereinafter; reference being had to the accompanying drawing, more or less diagrammatic in character, in which:

15 Figure 1 is a diagrammatic plan view, partly broken away, of a section of belt or fabric made up of helically coiled wires, with selvage-forming wires at the marginal edges of the same, within the scope of my invention.

20 Fig. 2 is a diagrammatic sectional view transversely of the belt or fabric.

Fig. 3 is a similar view illustrating a modification within the scope of my invention.

25 Fig. 4 is a fragmentary plan view, considerably enlarged, of a portion of the belt and one selvage of the same.

Fig. 5 is a sectional view on the line V—V, Fig. 4.

Fig. 6 is an edge view of a portion of one marginal edge of the belt, looking in the direction 30 of the arrow a, Fig. 4, and

35 Figs. 7 and 8 are fragmentary diagrammatic views illustrating further modifications within the scope of my invention.

40 My improved belt is made up of a plurality of helically twisted wires, some of which have a dextrorsal twist; that is to say, a right-hand twist, as indicated at 1, while the others have a sinistrorsal twist; that is to say, a left-hand twist, as indicated at 2, and the main or body portion of the fabric making up the belt is substantially the same as that illustrated in my prior application before referred to.

45 The dextrorsal wires are interlocked with each other and interlaced with the sinistrorsal wires, while the sinistrorsal wires are interlocked with each other and interlaced with the dextrorsal wires. The result of this arrangement is the production of a belt of double thickness throughout its major portion, the surfaces of which belt present, alternately, sinistrorsal and dextrorsal wires. To stiffen the belt transversely, I introduce straight wires or rods 3, which pass through the bights of the several interlaced and interlocked wires. These wires may be retained in place 50 transversely of the belt by bending one or both ends of the same in line with the belt, as indicated at 3^a. By preference, one end only of each straight wire or rod is bent over, and the bent-over portions are arranged alternately at each 55 marginal edge of the belt.

60 In providing the raised margins or selvages at the edges of the belt made up of the short interlocking wires, one selvage presents on the upper surface dextrorsal wires, and the opposite selvage sinistrorsal wires so that, if it be necessary that such marginal portions of the belt engage driving rolls or drums, there will be no danger of lateral displacement.

65 In preparing these elevated selvages or margins, I may proceed as follows:

70 At one edge or margin of the belt, more clearly shown in Fig. 5, I interlock with the helices of one set of the belt wires—in this instance, the sinistrorsal wires indicated at 2—a series of short wires 5 of sinistrorsal twist which may have three

or four runs or helices, and these short wires have their ends anchored at 5^a to the sinistrorsal belt wires with which they are interlocked. Between the short selvage-forming wires 5, interlocked with the belt wires 2, I place other short selvage-forming wires 6, such wires 6 being interlocked with the short wires 5, but not with the belt wires, and having their ends anchored at 6^a to the short wires 5. By reason of the fact that these groups of selvage-forming wires overlie the ends of certain of the belt wires and are interlocked therewith, the elevated margins have portions in two planes, as clearly illustrated in Figs. 5 and 6; the portion in the lower plane being the group of short wires 5 interlocked with the belt wires and connected thereto and the portion in the upper plane consisting of the short selvage-forming wires 6 interlocked with the short wires 5 and connected thereto; the latter wires being interlocked with the belt wires. If it is desired to 20 have higher selvages, other short wires of the same twist may be interlocked with the short wires 6 and connected therewith, and so on until a selvage of the desired height is reached. The helices of the short wires 6 constituting the upper 25 plane of the elevated selvage at the opposite edge or margin of the belt extend in an opposite direction—right-hand or dextrorsal, for instance—and interlock with the alternate selvage-forming wires 5 which, in turn, are interlocked with the right-hand or dextrorsal belt wires 1. It will be understood that, while I prefer to have the elevated marginal edges of the belt made up of short wires of opposite twist—that is to say, the wires 30 at one edge (either edge) may be of right-hand or dextrorsal twist, while the wires at the opposite edge may be of left-hand or sinistrorsal twist—it is within the scope of my invention to employ short selvage-forming wires of the same 35 twist to form the elevated margins at each edge 40 of the belt.

45 While, in most instances, the elevated margins or selvages will be disposed on one side or surface of the belt, it is within the scope of my invention to provide the elevated margins or selvages on both sides or surfaces of the belt so that superposed runs of the same employed as carrying surfaces will have elevated margins or selvages. Such an arrangement is illustrated diagrammatically in Fig. 3, the elevated selvages on one side 50 or surface being indicated at A, and those on the other side or surface being indicated at A'.

55 It is also within the scope of my invention to employ the short helically twisted wires in elevated zones longitudinally of the belt and intermediate the edges of the same, and such arrangement is illustrated diagrammatically in Fig. 7; an intermediate longitudinal zone of short wires in elevated position being indicated at A², and being built up in a manner substantially, if not exactly, similar to the manner of forming the elevated selvages; the ends of the short wires being similarly connected. A plurality of the elevated zones may be employed.

60 While I have illustrated and described the principal feature of my invention as comprising elevated portions extending longitudinally of the belt at the marginal edges thereof, or at some point (or points) intermediate the marginal edges and longitudinally of the belt, it is within the scope of my invention to introduce additional wires overlying and interlocking with the belt wires and extend the same transversely the full width thereof in elevated positions and at regularly spaced intervals for the purpose of providing 65 70 75 80 85 90 95 98

ing flights or carrying portions, particularly advantageous if the belt has inclined runs. Such arrangement is illustrated diagrammatically in Fig. 8 wherein the transversely arranged elevated portions are indicated at B.

5 The straight cross-wires or rods 3 may have one end bent at an angle, as indicated at 3^a, Figs. 1, 4, and 6, to prevent displacement transversely of the belt, or such ends may be bent into positive engagement and looped with an adjacent belt wire. These wires or rods may be employed with all forms of belts illustrated.

10 Various modifications may be made in the foregoing embodiments of my invention without departing from the spirit and scope thereof as set forth in the appended claims.

I claim:

1. A belt made of two sets of transversely arranged helically twisted wires one set having one 20 twist and being interlocked and the other set having an opposite twist and being interlocked; said sets of wires being interlaced with each other and providing selvages at each side of the belt, and elevated selvages for said belt consisting of 25 short helically twisted interlocking wires some of which are interlocked with the ends of a layer of belt wires and all of which are in parallel relation with respect to said belt wires.

2. A fabric comprising right and left hand coil strands; said right hand coil strands being spirally fed one into another and the left hand coil strands being spirally fed one into another, with the right and left hand coil strands interlacing with one another to prevent separation, and an elevated selvage at the edges of said fabric longitudinally of the same and transversely of the coiled strands making up the same; said selvage comprising short helically twisted wires interlocking with each other and interlocked with a layer of the fabric strands and arranged in parallel relation with respect thereto.

3. A fabric comprising right and left hand coil strands; said right hand coil strands being spirally fed one into another and the left hand coil strands being spirally fed one into another, with the right and left hand coil strands interlacing with one another to prevent separation, and an elevated portion longitudinally of said fabric and 20 transversely of the coiled strands making up the same; said elevated portion comprising short helically twisted wires interlocking with each other and interlocked with a layer of the fabric strands and disposed in parallel relation with respect 25 thereto.

RAYMOND J. GUBA.
